ASSIGNORS TO JACIEL PERFUMERS, INC., OF NEW YORK, N. Y., A CORPORATION
OF NEW YORK

FOLDING CONTAINER

Application filed May 7, 1928. Serial No. 275,648.

This invention relates to containers holding a pack of separate sheets of flexible material, such as facial towelettes or the like, so that they are in position for use at all times, 5 and so that one sheet at a time may be removed without handling or otherwise disturbing the remainder of the sheets in the pack. These facial towelettes have been supplied heretofore in cartons of the ordinary 10 type in which the entire pack of towelettes has been folded so that in order to remove one towelette for use the entire pack of them must be removed from the carton and unfolded. Even where the packs of towelettes 15 have been provided in an unfolded state, the removal of one of the towelettes disturbs the others because they tend to stick together, and as these towelettes are usually provided in relatively large sizes so that they may be 20 readily handled and used, a carton in which they are kept in a flat position must necessarily be larger than the nature of the contents warrants.

It is the principal object of this invention 25 to provide a container for a pack of facial towelettes or other sheet material of a similar nature from which the towelettes may be removed one by one without handling or otherwise disturbing the remaining towelettes in the pack, and also to provide a container which may be folded so that while the towelettes are withdrawn therefrom in a flat position, the container, when not in use, takes up only a small amount of space. Because 30 of the particular arrangement of the towelettes in the carton when it is in open position for use, it is not necessary to remove the whole pack of towelettes in order to remove one of them, so that the unused towelettes 35 remain undisturbed and do not become soiled or crumpled from excessive handling.

In accordance with this object the invention resides in a container consisting of a main portion having a bottom and three sides 45 and a secondary portion hinged at the open side of the main portion and arranged so that it may be folded within the main portion so as to lie flush with the top thereof. The secondary portion is provided with an envelope of approximately half the depth of

the main portion, and which opens into the main portion at the hinged edge between the two portions. The pack of paper towelettes is adapted to be inserted in the envelope and lie on the bottom of the main portion so that approximately half of the pack lies in each portion of the container. When the secondary portion is folded into the main portion in the manner described, the envelope thereof carries half of the pack with it so that this half is folded over the half remaining in the main portion, whereby the pack of towelettes is folded over once. In this way, the container occupies half the space in its closed position as it does in its open position. When the container is in open position, the top towelette of the pack may be removed by reaching into the main portion and pulling this towelette from under the upper flap of the envelope. The envelope is so arranged that it confines approximately half of the pack of towelettes so that the removal of one or even several of them does not disturb the remainder.

This new container is made in a novel way 75 of any suitable material, but is particularly adapted to be made from cardboard which is initially so formed that it may be folded and secured without glue or other fastening means to produce the container from one piece of cardboard and in such a way as to make a strong and durable structure which may be used repeatedly until all of the towelettes initially contained therein have been used.

For a better understanding of the invention, reference is made to the accompanying drawings, in which

Figure 1 is a perspective view of the container, in open position and containing a pack of paper towelettes or other similar sheet material;

Fig. 2 is a perspective view of the carton in closed position;

Fig. 3 is a fragmentary view of Fig. 1 with the pack of towelettes removed and showing the construction of the container as made from cardboard.

Fig. 4 is a fragmentary perspective view also showing the construction of the carton;

Fig. 5 is a vertical section through the con-

tainer with a pack of towelettes therein when in closed position; and

Fig. 6 is a development of the cardboard container.

5 In these drawings the main portion of the container consists of sides 10 and 11, end 12, and bottom 13, this bottom being continued to form the bottom of the secondary or top portion when the container is in open
10 position. The secondary portion consists of sides 14 and 15, end 16, and top 17. The pack of towelettes 18 is placed in the carton so that approximately half of the pack lies in the main portion and the other half lies
15 in the secondary portion within the envelope formed by sides 14 and 15, end 16 and top 17. In order to conform to the shape of the pack of towelettes when it is in folded position, the free edges of ends 14 and 15 are bevelled
20 as indicated at B in Figs. 1, 2, 5, and 6, and the top edges of these sides 14 and 15 are tapered toward their free ends as indicated at T in Figs. 1, 2, 5 and 6. The purpose of beveling the free ends B of sides 14 and 15
25 is to accommodate the thickness of the pack 18 at the fold thereof as shown in Figs. 2 and 5, while the purpose of tapering sides 14 and 15 at T toward their free ends is to confine the pack of towelettes while in the envelope
30 so that pressure is applied toward the center of the pack whereby the pack is prevented from rolling or curling up because of friction or sticking when a towelette is removed from the pack.

35 In case it is desirable to make the container of cardboard, this container being the carton in which the towelettes are distributed to the user, the cardboard blank is preferably shaped as shown in Fig. 6. Here the bottom
40 is made up of sections 13', 13'', and 13''', being folded as indicated by the dotted lines. The sides 10 and 11 of the main portion are provided with auxiliary portions 10', 10'', and 11', 11'', respectively, portions 10' and 11''
45 being each provided with a triangular notch 19. The end 12 of the main portion is provided with auxiliary portions 12' and 12'', the sides of 12'' being shaped to flare outwardly so as to provide tongues 20. The end
50 12, which includes auxiliary portions 12' and 12'', is adapted to be folded in two places as indicated by the dotted lines in Fig. 6. Attached to the edges of sides 10 and 11 are
55 rectangular side-pieces 21 and 22, respectively. The main portion of the container is assembled by folding the blank along the dotted lines shown in Fig. 6, sides 10 and 11 and end 12, with their auxiliary portions being folded upwardly. Side-pieces 21 and
60 22 are adapted to be folded inwardly so as to lie parallel with end 12. Auxiliary portions 10' and 10'' are adapted to be folded inwardly so as to overlie 10, and auxiliary portions 11' and 11'' are adapted to be folded
65 inwardly to overlie 11. Then portions 12'

and 12" are folded inwardly so as to overlie portions 12, 21, and 22, whereby tongues 20, will be caught in the triangular notches 19 in 11', so that the main portion of the container stands erect as a double walled structure 70 without the need of glue or fastening other than the tongues 20 fitted into notches 19. Figures 3 and 4 illustrate the manner of folding the main body, Fig. 3 particularly illustrating the appearance of the main portion 75 when in final folded position.

The secondary portion of the carton is formed around 13', end 16 and flap 16' being attached thereto at the end, while side-pieces 14 and 15 are attached thereto at the sides. The top 17 of the secondary portion includes two flaps 17' and 17'', the former being provided with notches and the latter with tongues which are adapted to fit into these notches. 85
In order to fold the secondary portion into shape, the various portions thereof are folded along the dotted lines shown in Fig. 6, then flaps 17' and 17'' are folded over flap 16' and joined together to complete the envelope of the secondary portion in the manner illustrated in Fig. 3. 90

In the cardboard container described, flap 16' falls downwardly so as to continuously bear against the top sheet of the pack of towelettes with sufficient pressure to confine the pack so as to aid the configuration of the envelope in preventing the disturbance of the towelettes contained therein when the top one is removed. 100

It will be seen that the container of this invention provides a simple expedient for the successive removal of paper towelettes one by one without the necessity of removing the whole pack from the container, whereby they are not disturbed or soiled by handling. While such a container made of cardboard has been particularly described, it is to be understood that it may be made from any suitable material of a temporary or permanent nature, and that various changes may be made in the design of the container within the scope of the invention.

We claim:

1. A container for a pack of sheet material, which comprises a receptacle open at the top and one side, a second receptacle having only one open side, and a flexible web connecting both receptacles at their open sides, whereby the second receptacle is adapted to be folded into the first receptacle about the flexible web as a hinge. 115 120

2. A container for a pack of sheet material, which comprises a receptacle open at the top and one side only, a second receptacle open at one side only, said receptacles communicating through their open sides, and flexible connections between the receptacles at their open sides, whereby said pack may be partially enclosed by the second receptacle and 130

be partially exposed through the open top of the first receptacle.

3. A container comprising two receptacles having a common bottom and communicating adjacent openings, one receptacle having a top and being of less depth than the other receptacle, and the other receptacle having an open top for receiving said one receptacle.

4. A container for a pack of sheet material, which consists of a receptacle open at the top and one side, a second receptacle open at one side only and of less depth than the first receptacle, a flexible web joining said receptacles at their open sides, whereby the second receptacle may be folded into the first receptacle, and means forming part of the second receptacle for bearing against the top of the pack in the container.

5. A container for a pack of sheet material, which consists of a receptacle open at the top and one side, a second receptacle open at one side only and of less depth than the first receptacle, and a web flexibly joining the two receptacles at their open sides, this web having a width between receptacles approximately equal to the depth of the first receptacle, whereby the second receptacle may be folded into the first receptacle so as to be flush with the top edge of the latter.

6. A container for a pack of sheet material comprising a receptacle open at the top and one side, a second receptacle having only one side open, the top of said second receptacle being offset from the bottom at the open side thereof, and a web flexibly joining both receptacles at their open sides, whereby the receptacles communicating through the open sides and the second receptacle may be folded into the open top of first receptacle about said web as a hinge.

7. A container for a pack of sheet material comprising a receptacle open only at the top and one side, a second receptacle having only one side open, the closed side of the second receptacle being wider than the opposite open side thereof, and a web flexibly joining the receptacles at their open sides, whereby the receptacles communicate through their open sides and the second receptacle may be folded into the first receptacle about said web as a hinge.

8. A container for a pack of sheet material, comprising a web forming the bottoms of two adjacent receptacles, the first receptacle being formed by two side-pieces interlocking with an end piece and having an open side adjacent the second receptacle, and the second receptacle being joined by interlocking side and top pieces and an end piece and having an open side in communication with the open side of the first receptacle.

9. A container for a pack of sheet material, comprising a sheet forming the bottoms of two adjacent receptacles, the first receptacle being formed by two side-pieces interlocking

with an end piece and having an open side adjacent the second receptacle, and the second receptacle being formed by interlocking side and top pieces and an end piece and having an open side adjacent the open side of the first receptacle, the second receptacle being of approximately half the depth of the first receptacle and adapted to be folded into the first receptacle.

10. A container for a pack of sheet material, comprising a sheet forming the bottoms of two adjacent receptacles, the first receptacle being formed by two side-pieces interlocking with an end piece and having an open side adjacent the second receptacle, the second receptacle being formed by interlocking side and top pieces and an end piece and having an open side adjacent the open side of the first receptacle, and a projection on the said end piece of the second receptacle adapted to bear upon the top of the stack in the container.

11. A container for a pack of sheet material, comprising a web forming the bottoms of two adjacent receptacles, the first receptacle being formed by two side-pieces interlocking with an end piece and having an open side adjacent the second receptacle, and the second receptacle being formed by interlocking side and top pieces and an end piece and having an open side adjacent the open side of the first receptacle whereby the receptacles communicate through their open sides, the top of the second receptacle being offset from the bottom at the open side thereof.

12. A container for a pack of sheet material, comprising a sheet forming the bottoms of two adjacent receptacles, the first receptacle being formed by two side-pieces interlocking with an end piece and having an open side adjacent the second receptacle, and the second receptacle being formed by interlocking side and top pieces and an end piece and having an open side adjacent the open side of the first receptacle, the top of the second receptacle tapering toward the bottom at the open side thereof.

In testimony whereof we affix our signatures.
